UNITED STATES PATENT OFFICE.

GEORGE L. THOMPSON, OF CHICAGO, ILLINOIS.

DESIGN FOR A BICYCLE-FRAME.

SPECIFICATION forming part of Design No. 29,244, dated August 16, 1898.

Application filed July 5, 1898. Serial No. 686,177. Term of patent 7 years.

To all whom it may concern:

Be it known that I, GEORGE L. THOMPSON, of Chicago, in the county of Cook and State of Illinois, have invented and produced a new and original Design for a Bicycle-Frame, of which the following is a specification.

My novel design consists in a bicycle-frame of the general type commonly known as the "diamond" frame, and embraces as its distinctive features the novel design produced by the peculiar conformation of the rear-fork members a a' , respectively, embodied in a frame made in other respects as usual—*i. e.*, made of ordinary circular tubing.

In my novel design each fork member is made of angular contour in cross-section, so as to present to view a plurality of flat faces a^2 throughout the principal part of its length, and the two crowns b b' , by means of which the several pairs of forked members are united to each other and to the rest of the frame, are oval or U-shaped, substantially as shown in the accompanying drawings, wherein—

Figure 1 is a perspective view of the frame as a whole, and Fig. 2 is a transverse sectional view taken on line 2 2 of said Fig. 1.

The tip ends a^3 of the fork members and

the oval crowns, with which the latter are united, are made smooth and of generally oval form in cross-section, thereby contrasting with the angular-shaped portions of the forks, the flat faces of which latter are arranged symmetrically and substantially co-extensive with each other and merge into the smooth or oval portions in the form of gracefully-tapered points or end portions a^4 , thereby accentuating the characteristic appearance of the design. The said fork members b b' are united with the upper portion of the seat-poststandard and with the crank-hanger, respectively, by single straight-tube sections c c' .

I claim as my invention—

The design for a bicycle-frame, substantially as herein shown and described. 45

In testimony that I claim the foregoing as my invention I affix my signature hereto, in the presence of two subscribing witnesses, this 30th day of June, A. D. 1898.

GEORGE L. THOMPSON.
